UNITED STATES PATENT OFFICE

2,480,451

TOOL

Miguel de la Torre, Chicago, Ill., assignor to Burgess Battery Company, Freeport, Ill., a corporation of Delaware

Application May 18, 1945, Serial No. 594,557

9 Claims. (Cl. 172—126)

1

This invention relates to improvements in electrical reciprocating tools which may be used for dental plugging and for tamping plastic masses in general, and also for engraving, embossing and cutting materials such as metal, wood, plastics, glass and the like.

It is the object of the invention to provide an improved tool of the character mentioned which may be operated from any convenient electric outlet or other source of electric energy.

It is another object of the invention to provide an improvement in tools of the character mentioned which facilitates their operation, whether the operator is an expert or an inexperienced person, and which renders their operation more satisfactory.

A further object of the invention is to provide a tool of the character mentioned in which the working point or other surface remains in the inactive state until it is pressed against the object which is being worked upon.

It is a further object of the invention to provide a tool of the character mentioned which is rendered operative by pressing the working point or other surface against the object which is being worked upon.

Other objects and advantages will become apparent as the following description progresses which is to be taken in connection with the accompanying drawings in which:

Fig. 1 is a longitudinal sectional view of a vibratory tool in accordance with the invention;

Fig. 2 is a side view, taken at right angles to Fig. 1;

Fig. 3 is a transverse sectional view of a portion of the tool, taken along line 3—3 of Fig. 1;

Figs. 4, 5 and 7 are longitudinal sectional views of different modifications of the vibratory tool of the invention;

Fig. 6 is a transverse sectional view taken along line 6—6 of Fig. 5; and

Fig. 8 is a rearward view of a part of the device of Fig. 7.

Referring to Fig. 1, the structure consists of a hollow tubular stem 10 of non-magnetic material, such as brass or copper. Stem 10 is open at both ends and has an opening 11 in its side adjacent the rearward end. Attached to the surface of the stem 10, by welding, soldering or otherwise, is a shell 12 containing an electromagnet consisting of an E-shaped ferrromagnetic core 13 and a winding 14 surrounding the middle leg of the core and insulated from the core by the insulating material 15. The legs of the E extend rearwardly and an armature 16 extends across their

2

rearward ends. The side of shell 12 remote from stem 10 extends rearwardly beyond the end of the core 13 and is then turned inwardly to form the flange 17 which engages the rearward surface of the end of armature 16 and holds said end substantially against the adjacent core leg. The opposite end of the armature projects through opening 11 into the hollow stem 10, said opening 11 providing sufficient clearance to permit the oscillatory motion of the end of the armature. A casing 18 of non-conductive material, such as synthetic resin, encloses the shell 12 and the stem 10 and the ends 19 of the coil 14 extend through the casing wall and are adapted to be connected to a source of alternating current energy. Casing 18 has openings in the ends thereof through which the ends of stem 10 are exposed. The casing is split, as shown in Fig. 2, and two halves are held together by metal rings 20 which encircle flanges 21 which project outwardly at the edges of the openings of the casing.

The forward end portion of the bore of stem 10 is enlarged as shown at 22, and rearwardly of the portion 22, said bore is internally screw threaded and receives a threaded bushing 23, which may be moved to any desired advanced or retracted position with respect to the stem 10. The bushing 23 carries the lock nut 24 which is adapted to lock bushing 23 in position with respect to stem 10.

A drive rod or plunger 25 extends in axially slidable relation through the bushing 23 and rearwardly into the hollow stem 10. A chuck 26 is fixed to the forward end of the drive rod and is adapted to reciprocate in the bore 27 of bushing 23. A tool 28, which is shown as being a blunt tamping tool, but which may be an engraving needle, a knife, or other suitable tool, is inserted in chuck 26 and is clamped in place by the screw 29. The rearward end portion of bushing 23 has two diametrically opposite longitudinal slots 30 therein and drive rod 25 has two thin flat lateral projections 31 which are adapted to reciprocate longitudinally in said slots. The slots 30 and projections 31 prevent the turning of the chuck 26 and the tool 28 while the device is being operated.

Drive rod 25 ends at an intermediate portion of stem 10 and a second axially slidable rod 32 is located within the bore of the stem and between rod 25 and the armature 16. Rod 32 has lateral projections 33 disposed on opposite sides thereof and cooperating with the walls of the bore of stem 10 to maintain the rod 32 in alignment with rod 25. A sleeve 34 is disposed slidably upon rod

25 rearwardly of the projections 31, and a sleeve 35 is disposed upon rod 32 forwardly of projections 33. Disposed loosely about the adjacent ends of rods 25 and 32 and between sleeves 34 and 35 is a compression spring 36. Said compression spring, through the sleeves 34 and 35 and projections 31 and 33, urge rods 25 and 32 apart. The position of these parts in the base of stem 10 is adjustable by advancing and retreating bushing 23 in stem 10. The arrangement is preferably such that with projections 31 resting against the forward ends of slots 30 and armature 16 resting against the rearward surface of the core 13 and also substantially in abutting relationship with the rearward end of rod 32 and the adjacent ends of rods 25 and 32 spaced apart a substantial distance as shown in Fig. 1, there is substantially no compression on spring 36. The bushing 23 may be turned into the stem until the rod 32 pushes armature 16 away from coil 13 a slight distance but it should not be turned so far that, when the magnet is energized and attracts the armature, rod 32 strikes rod 25, and the armature is prevented from making contact with the magnet. Shoulder 37 is provided upon bushing 23 to insure that such an adjustment will not be made.

The rearward end of the bore of stem 10 is internally threaded and receives a threaded adjusting bolt 38. A spring 39 surrounds the shank of said bolt and extends between the bolt head and the end of stem 10 to assist in maintaining the bolt in any adjusted position. The length of the stroke of armature 16 is regulated by adjusting the position of bolt 38.

In operation, the device is connected to a source of alternating current energy and the armature 16 is attracted by the electromagnet and urged forwardly into contact with the rearward surface of core 13 twice during each cycle of said energy source. When the armature is first drawn against the core, it remains in such position until the tool 28 is pressed against the object to be worked upon. To bring the device into operation, the operator presses the end of the tool 28 against the work, for example, the filling material in the cavity of a tooth to be filled, whereupon the chuck 26 and rod 25 are urged rearwardly and spring 36 transmits such pressure through the rod 32 to armature 16. As a result, the free end of the armature is moved rearwardly between impulses and undergoes an oscillatory motion about the opposite end which is restrained by flange 17. Such oscillation is transmitted to rod 32 and results in contraction and expansion of spring 36. During this time the pressure exerted by tool 28 against the work is only slight, whereby the rod 25 moves rearwardly only a short distance, less than enough to bring it into the sphere of action of the rod 32. The operator increases the pressure of the tool against the work and the drive rod 25 is moved rearwardly farther until it comes into the sphere of action of rod 32, whereupon the end of rod 32 strikes the end of rod 25 a blow with each impulse of the armature 16. This occurs when drive rod 25 has been moved rearwardly sufficiently that the length of rod 32 exceeds the distance between the rearward end of drive rod 25 and armature 16 when the latter is in position against core 13. Thereafter, as the pressure exerted by the tool 28 against the work is increased, the energy of the impulses becomes greater because the drive rod is moved a greater distance. Also, the armature 16 moves a greater distance rearwardly and as

its travel increases its velocity and the strength of its blows become greater. To stop operation, it is only necessary to discontinue pressing tool 28 against the work.

Under normal conditions, therefore, that is, when the tool 28 is not pressed against the work, the drive rod 25 is not in positive motion transmitting relationship with the armature 16 and it is possible to rest the end of the tool 28 against the work while it is stationary and placement can be accurately controlled. This is an important advantage in many applications, such as the impacting of dental filling material, the tracing of designs in engraving, etc. Also, the device is motionless and quiet when it is not actually in operative position against the work, which is an advantage. In addition, the strength of the impulses of the tool is readily regulated by controlling the pressure of the tool against the work. Very light impulses can be obtained by using a slight pressure, which is not sufficient to bring the drive rod 25 into the sphere of action of the rod 32. Such light impulses are transmitted from rod 32 to rod 25 by spring 36 alone and make possible very delicate work. On the other hand, very strong impulses can be obtained by pressing the tool against the work with relatively heavy pressure, in which case strong sharp blows are delivered by rod 32 against drive rod 25. Any desired strength of impulse can be obtained between the two extremes by properly regulating the pressure of the tool against the work. When the term "normal" or "normally" is used herein in the specification and claims it means the condition which exists when rearward pressure is not exerted against the drive rod or plunger, such as would be caused by pressing the tool against the work.

As explained heretofore, it is preferred that spring 36 exert substantially no pressure against rod 32 and armature 16 in the at rest position. However, bushing 23 may, if desired, be threaded farther into stem 10 so that sufficient pressure is normally exerted by said spring to move the armature away from the core 13 and the said armature will undergo a relatively short vibratory action. This will not affect drive rod 25 and tool 28, since projections 31 of drive rod 25 will remain in position against the forward ends of slots 30 in bushing 23, and pulsations will not be transmitted to the drive rod and tool until the tool is pressed against the work sufficiently to move the projections 31 rearwardly in slots 30.

The modification illustrated in Fig. 4 is similar to that shown in Fig. 1 except for the construction of the drive rod and the spring which is associated with it. With the exception of the drive rod and spring, the parts of this modification will be designated by the same numerals as the corresponding parts of the modification of Fig. 1. The drive rod 45 extends all of the distance from the chuck 26 to a point adjacent to the forward surface of the armature 16. The drive rod 45 has lateral projections 46, which serve as a guide for the rearward end thereof, and projections 47 cooperating with slots 30 of bushing 23. A pin 48 extends through the drive rod at a point adjacent to the rearward end and the compression spring 49 surrounds the rearward end of the drive rod 45 and extends between pin 48 and armature 16. In this modification, the position of bushing 23 in stem 10 is preferably such that armature 16 normally rests against core 13, that is, with projections 47 of drive rod 45 resting against the forward ends of slots 30, spring 49 exerts sub-

stantially no pressure against armature 16, and the rearward end of drive rod 45 is spaced forwardly of armature 16.

The operation of this modification is similar to that of the modification of Fig. 1. With no rearward force applied to the tool 28, the device may be connected to a source of alternating current energy and armature 16 will remain stationary in position against core 13. The tool 28 may, therefore, be placed against the work while it is at rest before it undergoes vibratory action. Then, as it is pressed against the work, the drive rod is moved rearwardly and compression is exerted by spring 49 against armature 16 urging the latter rearwardly, whereupon the armature begins to undergo vibratory motion. This produces a series of light impulses in the tool 28 which are sufficient to produce a light tapping action or a delicate engraving action with an engraving needle. As the tool is pressed harder against the work, the compression exerted by spring 49 against the armature increases and the latter undergoes a more vigorous oscillating motion. At the same time, the rearward end of drive rod 45 is moved rearwardly until it comes into the sphere of action of armature 16 and the latter delivers a series of blows to the drive rod, which are transmitted to the tool 28.

In the modification shown in Fig. 5, the hollow tubular stem 50 has a bracket 51 attached to its rearward end, as by welding, said bracket diverging rearwardly and being attached, as by welding, to a substantially U-shaped shell 52, which is channel-shaped in cross section and encloses the end legs and body portion of a laminated ferromagnetic core 53. Core 53 is substantially E-shaped, the middle leg of the E being relatively short as shown. An annular winding 54 surrounds the middle leg of the core 53 and extends rearwardly a considerable distance beyond the end of said middle leg. The ends 59 of the winding 54 are adapted to be connected to a suitable source of alternating current electrical energy. The rearward end of shell 52 substantially coincides with the rearward end of winding 54 and the outer legs of the core 53 extend rearwardly beyond the winding 54 and flanges 55 are attached to said extending core portions by bolts 60 and extend inwardly.

A substantially T-shaped armature 56 is adapted to cooperate with the core 53 and has the trunk thereof extending forwardly into the central cavity of the annular winding 54 and the arms thereof extending laterally into closely adjacent relationship to the outer legs of the core 53.

A rod 57 is fixedly mounted in an opening in the forward portion of armature 56 and projects forwardly in axially slidable relationship through openings in core 53, shell 52 and bracket 51 and into the bore of stem 50, the forward end of said rod 57 occurring at an intermediate portion of the said stem 50. The rearward end portion of the bore of stem 50 is enlarged as shown at 58 to accommodate a compression spring 62 which surrounds rod 57 and extends between the shoulders formed at the forward end of the enlargement 58 and the pin 63 which extends through rod 57. A second compression spring 64 is arranged between pin 63 and the forward surface of shell 52. The springs 62 and 64 are so constructed and arranged that normally, that is, in the absence of any magnetic urge upon armature 56, the forward end of said armature is maintained in spaced relation to the middle leg of core 53. Upon energization of the device, the armature 56 is at-

tracted by the core 53 twice during each cycle and it together with rod 57, undergoes a reciprocating action.

The forward end of the bore of stem 50 is enlarged as shown and internally threaded and receives the externally threaded bushing 65. The rearward end of the bore of bushing 65 is internally threaded and receives an externally threaded nut 66 which has a diametric slot 67 in the rearward surface thereof whereby it may be threaded into and out of the bushing 65 by means of a screw driver.

The forward portion of bushing 65 is substantially closed except for the central opening extending therethrough and communicating with the bore thereof. Said opening is preferably of angular, for example square, configuration. The forward portion of the drive rod 68 extends axially through the bore of bushing 65 and is of angular configuration in cross section to fit slidably in the opening of the bushing 65. The rearward portion of drive rod 68 is cylindrical in cross section and projects through an opening in collar 69 and beyond the rearward end of bushing 65 into spaced adjacent relationship to rod 57. A collar 69 is provided on rod 68 at an intermediate portion thereof within bushing 65, and a compression spring 70 surrounds the rod 68 between collar 69 and the head of bushing 65 and a second compression spring 71 surrounds said rod between collar 69 and nut 66. A chuck 72 is fastened to the forward end of drive rod 68 and is adapted to receive a tool 73. The arrangement of springs 70 and 71 is such that drive rod 68 is held resiliently with chuck 72 spaced forwardly of bushing 65 and the rearward end of drive rod 68 is in spaced relation to the forward end of rod 57.

In operating the device, it is first connected to a source of alternating current energy, whereupon armature 56 and rod 57 undergo reciprocating action. Such action, however, is not transmitted to drive rod 68 and chuck 72 because the adjacent ends of rods 57 and 68 remain out of contact with each other. The tool 73 is then pressed against the work and rod 68 is thereby moved rearwardly until it comes into the sphere of action of rod 57, whereupon pulsating blows are applied to the drive rod 68 and transmitted to the tool 73. The arrangement is preferably such that the rearward travel of rod 57 always exceeds that of drive rod 68 whereby rod 57 delivers sharp blows to the drive rod. Such arrangement is not required, however, and chuck 72 may be so spaced from bushing 65 that it is adapted to travel co-extensively with rod 57 whereby the two rods remain in contact throughout their reciprocating motion.

A casing, which is not shown, may be provided to enclose the stem 50 and the electromagnet comprising the core 53 and winding 54, if desired.

In the modification shown in Fig. 7, the stem 75 projects forwardly from and is attached, as by welding, to a shell 74 which encloses an electromagnet comprising the laminated ferromagnetic core 76. Said core is substantially E-shaped with the middle leg of the E shorter than the outer legs and with the ends of the outer legs turned inwardly toward each other. The middle leg of the core is surrounded by an annular winding 77, the ends 78 of which are adapted to be connected to a source of alternating current energy. An armature 79 is adapted to reciprocate towards and away from the middle leg of the core 76 and

between the outer legs of said core. A rod 80 is rigidly fixed in an opening in armature 79 and extends forwardly through openings in core 76 and shell 74 and into the bore of stem 75. A pin 81 extends through rod 80 at a point spaced from core 76 and a compression spring 82 surrounds the portion of rod 80 between pin 81 and core 76. The forward end portion 83 of rod 80 is of reduced diameter forming a shoulder 84. At a point opposite an intermediate portion of the reduced portion 83 of the rod an opening 85 is provided in stem 75 and a lever 86 is mounted pivotally in said opening and has one end extending outwardly therefrom and the other end, which is bifurcated as shown in Fig. 8, extending inwardly and embracing the portion 83 of rod 80. The bore of stem 75 is reduced at a point slightly forwardly of lever 86 and a bushing 87 is arranged in said bore and resting against the shoulder formed by the said reduction. Lever 86 normally rests against the surface of bushing 87. The end portion 83 of rod 80 extends through the bushing 87 and ends at a point slightly forwardly thereof. A compression spring 88 surrounds said rod portion 83 between lever 86 and shoulder 84.

A bushing 90 is threadedly received in the forward end of the bore of stem 75 and a drive rod 91 extends in axially slidable relationship through bushing 90 and into the hollow bore of stem 75 and abuts the end of rod 80. A pin 92 passes through drive rod 91 at a point adjacent its rearward end and compression spring 93 is arranged between pin 92 and the rearward end of bushing 90. A chuck 94 is fixed to the forward end of drive rod 91 and is adapted to receive the tool 95.

A sleeve-shaped handle member 96 of non-conductive material is arranged in slidable telescoping relationship over stem 75, with its rearward end normally resting against the forward surface of shell 74. Handle 96 has an opening 100 through which the projecting end of lever 86 extends. Handle 96 has its bore widened at a point adjacent the forward end thereof to form a shoulder against which a washer 97 rests. The portion of bushing 90 projecting forwardly from stem 75 is externally threaded and receives an adjusting nut 98 which is spaced forwardly from washer 97. A compression spring 99 is arranged between adjusting nut 98 and washer 97 and serves to urge handle 96 into abutting relationship with core 76.

In operating the device of Fig. 7, the springs 88 and 93 normally do not exert sufficient rearward force upon rod 80 to move armature 79 out of contact with the middle leg of core 76. The device is first connected to a suitable source of energy, and the armature 79 and the tool 95 remain stationary in their normal positions. The tool is then pressed against the work. Such pressure causes drive rod 91 to move rearwardly until chuck 94 engages bushing 90, when the rearward motion of drive rod 91 stops. Rod 80 moves with drive rod 91 against the force of spring 82, and armature 79 is moved out of contact with the middle leg of core 76. At the same time, the said manual pressure moves handle 96 forwardly with respect to stem 75 and causes lever 86 to turn upon its pivotal support and maintain spring 88 under compression. The armature is thereupon moved forwardly intermittently by the magnet, and the armature, rod 80 and drive rod 91 undergo a reciprocating motion. As the forward pressure exerted upon handle 96 is increased, the rearward pressure of spring 88 upon rod 80 increases and the travel of armature 79 and rod 80 becomes greater than the travel of

drive rod 91 and rod 80 strikes the drive rod a series of blows, which become stronger as the pressure against the work is increased. Spring 82 acts as a cushioning and stop means for the rearward motion of the armature 79 and rod 80. Spring 82 also assists in moving the armature 79 and rod 80 forwardly, and its effect is to increase the force of the blows upon drive rod 91. An opening 101 is provided in stem 75, which cooperates with a stop member 102 which projects inwardly from handle 96 to limit the forward motion of said handle. The pressure required to be exerted upon handle 96 to bring the device into operation may be regulated by advancing or retracting adjusting nut 98 upon bushing 90. This feature assists in providing a delicate adjustment of the force of the blow, which is desirable for dental impacting and also to adapt the device for different uses.

While several embodiments of the invention are illustrated and described, the modifications which may be made are not limited thereto, but various further changes and alterations will occur to those skilled in the art within the spirit of the invention as the same is set forth in the appended claims. In the modifications which have two aligned rods, instead of considering only the forwardly located rod as the drive rod, the two rods may be considered as separate sections of the drive rod. While the tool has been described as being operable by alternating current energy, it is also adapted for operation by pulsating direct current.

What is claimed is:

1. A vibratory tool, comprising an electromagnet, an armature adapted to be intermittently urged forward upon energization of said magnet, a plunger adapted to reciprocate axially and to carry a tool at the forward end thereof, means for guiding said plunger during axial motion thereof, means for limiting the forward motion of said plunger, resilient means for maintaining said plunger normally out of positive motion transmitting relationship with said armature, said plunger being movable rearwardly into positive motion transmitting relationship with said armature.

2. A vibratory tool, comprising an electromagnet, an armature adapted to be intermittently urged forward upon energization of said magnet, a plunger adapted to reciprocate axially and to carry a tool at the forward end thereof, means for guiding said plunger during axial motion thereof, means for limiting the forward motion of said plunger, means for positively transmitting the forward motion of said armature to said plunger, means including a spring for normally maintaining said plunger out of positive motion transmitting relationship with said armature, said plunger being movable rearwardly against the influence of said spring into positive motion transmitting relationship with said armature.

3. A vibratory tool, comprising an electromagnet, an armature adapted to be intermittently urged forward upon energization of said magnet, a plunger adapted to reciprocate axially and to carry a tool at the forward end thereof, means for guiding said plunger during axial motion thereof, means for transmitting forward motion from said armature to said plunger, means for stopping the forward motion of said plunger, spring means normally maintaining said plunger against said stop means and out of positive motion transmitting relationship with said armature, said plunger being movable rearwardly into

positive motion transmitting relationship with said armature.

4. A vibratory tool, comprising an electromagnet, an armature adapted to be intermittently urged forward upon energization of said magnet, plunger means adapted to reciprocate axially and to carry a tool at the forward end thereof, means for guiding said plunger means during axial motion thereof, said plunger means comprising separate aligned forward and rearward sections, the rearward section of the plunger means abutting the forward surface of said armature, spring means under compression between said plunger sections and normally maintaining the adjacent ends of said sections in spaced apart relationship, separate means for stopping the forward motion of said armature and said forward plunger section, said plunger stop means being so arranged that normally said armature rests against said armature stop means.

5. A vibratory tool, comprising an electromagnet, an armature adapted to be intermittently urged forward upon energization of said magnet, plunger means adapted to reciprocate axially and to carry a tool at the forward end thereof, means for guiding said plunger means during axial motion thereof, said plunger means comprising separate aligned forward and rearward sections, the rearward section of said plunger means abutting the forward surface of said armature, spring means normally maintaining said plunger sections apart, separate means for stopping the forward motion of said armature and said forward plunger section, said plunger stop means being so arranged that normally said armature rests against said armature stop means.

6. A vibratory tool, comprising an electromagnet, an armature adapted to be intermittently urged forward upon energization of said magnet, plunger means adapted to reciprocate axially and to carry a tool at the forward end thereof, means for guiding said plunger means during axial motion thereof, said plunger means comprising separate forward and rearward sections, means for positively transmitting forward motion from said armature to said rearward plunger section, spring means normally maintaining said forward plunger section out of positive motion transmitting relationship with said rearward plunger section, and means for stopping the forward motion of said forward plunger section, said forward plunger section being movable rearwardly against the influence of said spring means into positive motion transmitting relationship with said rearward plunger section.

7. A vibratory tool, comprising an electromagnet, an armature adapted to be intermittently urged forward upon energization of said magnet, a plunger adapted to reciprocate axially and to

carry a tool at the forward end thereof, means for guiding said plunger during axial motion thereof, means for stopping the forward motion of said plunger, spring means normally urging said armature in a rearward direction, separate spring means normally maintaining said plunger out of positive motion transmitting relationship with said armature, said plunger being movable rearwardly against the force of said last mentioned spring means into positive motion transmitting relationship with said armature.

8. A vibratory tool, comprising an electromagnet, an armature adapted to be intermittently urged forward upon energization of said magnet, means for stopping the forward motion of said armature, a hollow stem extending forwardly from said magnet, a plunger in said stem and adapted to reciprocate axially and carry a tool at the forward end thereof, means for transmitting forward motion from said armature to said plunger, means for limiting the forward motion of said plunger, a handle member arranged in slidably telescoping relation over said stem, and means for resiliently urging said armature rearwardly from said armature stop means upon movement of said handle means forwardly with respect to said stem.

9. A vibratory tool, comprising an electromagnet, an armature adapted to be intermittently urged forward upon energization of said magnet, means for stopping the forward motion of said armature, a plunger adapted to reciprocate axially and to carry a tool at the forward end thereof, means for guiding said plunger during axial motion thereof, means for stopping the forward motion of said plunger, resilient means for maintaining said plunger normally out of positive motion transmitting relationship with said armature, said plunger being movable at will rearwardly against the pressure of said resilient means into positive motion transmitting relationship with said armature, the arrangement being such that when said armature and plunger rest against their respective stop means said resilient means are under substantially no compression.
